United States Patent Office

Des. 215,748
Patented Oct. 28, 1969

215,748

BEVERAGE CAN HOLDER

Robert S. Wallace, 2706 S. Robertson Blvd.
Los Angeles, Calif. 90034

Filed Aug. 15, 1968, Ser. No. 13,150

Term of patent 14 years

Int. Cl. D9—99

U.S. Cl. D44—21

FIG.-1

FIG.-2

FIG. 1 is a perspective view from the front and top of a beverage can holder showing my new design; and FIG. 2 is a perspective view from the bottom and rear.

I claim:

The ornamental design for a beverage can holder, substantially as shown.
